UNITED STATES PATENT OFFICE.

ASHMEAD G. RODGERS, OF NIAGARA FALLS, NEW YORK, ASSIGNOR TO THE CARBO-RUNDUM COMPANY, OF NIAGARA FALLS, NEW YORK, A CORPORATION OF PENNSYLVANIA.

SCISSORS-SHARPENING ATTACHMENT FOR GRINDING-MACHINES.

1,063,391.

Specification of Letters Patent.

Patented June 3, 1913.

Application filed July 12, 1912. Serial No. 709,046.

To all whom it may concern:

Be it known that I, ASHMEAD G. RODGERS, of Niagara Falls, Niagara county, and State of New York, have invented a new and useful Improvement in Scissors-Sharpening Attachments for Grinding-Machines, of which the following is a full, clear, and exact description, reference being had to the accompanying drawings, forming part of this specification, in which—

Figure 1 is a front elevation of a machine embodying my invention. Fig. 2 is a side view of the same. Fig. 3 is a plan view, and Fig. 4 is a detail view of the scissors holding clamp.

My invention has relation to attachments for grinding machines for holding tools to be sharpened, and more particularly designed for use in sharpening scissors, shears, etc.

The object of my invention is to provide a simple and convenient attachment of this character, designed to be hand manipulated, and capable of universal movement with respect to the grinding face of the grinding wheel.

In the accompanying drawings, the numeral 2 designates the grinding wheel, which may be of any suitable character and which is mounted in a suitable bearing 3 in a frame 4. This frame is shown as having a clamp 5, by means of which it can be detachably secured to any suitable support 6.

7 is the handle of the machine which turns the wheel 2 through the multiplying gears 8.

In the preferred form of my attachment which I have illustrated, it comprises a base plate 9 which is adapted to be inserted between the upper surface of the support 6 and the upper lugs or jaws of the clamp 5, to be thereby secured when the grinding machine is clamped to the support. This plate has the upwardly projecting pivot lugs 10 between which is pivoted a bar member 11.

Pivoted to this bar member are two parallel links 12 connected at their upper ends by a transverse link 13, to which is pivoted the tool holding clamp. This clamp is shown as consisting of the bent jaws 14 and 15, provided with a clamping screw 16.

The parallel links 12 are preferably made adjustable in length; and for this purpose

each of them is shown as composed of two parts having the pin and slot connections 17.

When not in use the attachment will lie upon the support 6 in a substantially horizontal position. When in use, one blade of the shears or scissors to be sharpened is secured between the jaws 14 and 15 in the manner shown in Figs. 2, 3 and 4, and the attachment is swung upwardly on its pivotal connection with the base plate 9 into the position illustrated in the drawings. The attachment is manipulated by the hand to bring the edge of the tool to be sharpened into the desired position against the face of the grinding wheel and the pressure is also regulated by the hand of the operator.

The pivotal connection between the attachment and the base plate 9 provides for bodily movement toward and away from the grinding face of the wheel 2; the pivoted link members 12 and 13 provide for movement parallel with such grinding face and also for vertical adjustment; and the pivotal connection of the tool holding clamp with the transverse link 13 provides for an angular movement of the clamp and tool with respect to the grinding face.

My invention provides a simple form of attachment which can be readily applied to various types of grinding machines and which provides convenient means for holding and accurately grinding scissors, shears and other bevel edged tools; or straight edged tools.

The angle of the cut on the edge of the tool may be varied by shifting the adjusting plate 9 inwardly or outwardly with relation to the grinding machine, or by adjusting the position of the tool to be ground with relation to the jaws 14 and 15.

Owing to the universal movement which is permitted the tool holding clamp and tool, the tool can be readily manipulated by the operator.

I do not limit myself to the particular construction of the attachment which I have herein shown and described, and it is obvious that the details may be changed in various ways; for instance, a different form of base plate may be used, as well as one or more links, which may be parallel or not.

The attachment may be secured to the

grinder in other ways; the form of the tool holding clamp may be varied and other details may be changed.

What I claim is:

- 5 1. A tool holding attachment for grinding wheels, comprising a member adapted to be secured in fixed relation to a grinding wheel, a bar member pivoted to said member, a frame pivoted to the bar member and 10 arranged to swing at right angles to the movement of the bar member, and a tool holding clamp pivoted to the upper end of the frame; substantially as described.
- 15 2. A tool holding attachment for grinding machines, comprising a base member adapted to be secured in fixed relation to the grinding machine, a horizontal bar member pivotally mounted in said base member, parallel links pivoted to the bar member, 20 and a tool holding clamp pivoted to the upper ends of the links; substantially as described.
3. A tool holding attachment for grind-

ing machines, comprising a base member adapted to be secured in fixed relation to the grinding machine, a horizontal member pivotally mounted in said base member, links pivoted to the rotary member, the axis of said links being at right angles to the axis of the horizontal member, a tool holding clamp carried by said links, and means for adjusting the length of said links; substantially as described.

4. An attachment for grinding machines, comprising a parallel movement frame pivoted to move toward and away from and across the face of a grinding wheel, and a tool holding clamp pivotally supported on the said frame; substantially as described.

In testimony whereof, I have hereunto set my hand.

ASHMEAD G. RODGERS.
